UNITED STATES PATENT OFFICE

WILLIAM F. PUNTE, OF SYRACUSE, NEW YORK, ASSIGNOR TO CONTINENTAL CAN COMPANY, INC., OF NEW YORK, N. Y., A CORPORATION OF NEW YORK

SCORED CONTAINER WITH BREAKING TAB

Application filed June 5, 1930. Serial No. 459,342.

The invention relates to new and useful improvements in a closure for a metal container and more particularly to a closure having lugs for retaining the same in sealed position on said container.

An object of the invention is to provide a container having a body portion and an outside slip cover with holding lugs adapted to secure the cover in sealed contact with the body portion of the container, which holding lugs may be torn loose for releasing the cover.

In the drawings which show by way of illustration one embodiment of my invention: Fig. 1 is a view of the top portion of the container showing the cover in place and the lugs in retaining position.

Fig. 2 is a portion of the body blank before it is folded, with the fold line indicated thereon and also showing the score line where the lugs may be torn off.

Fig. 3 is an enlarged vertical detail through a portion of the cover and body showing a vertical sectional view through one of the holding lugs, with the holding lugs in place for securing the cover on.

Fig. 4 is a view similar to Fig. 3, but showing the lugs broken off and the cover raised.

The invention is directed broadly to a container having an outside slip cover, said container being provided with integral lugs for retaining said cover in positive sealed relation thereon. These lugs are preferably formed integral with the body blank of the container before it is rolled and locked into its usual cylindrical form. Score lines are provided and so positioned at the base of said lugs that they may be readily broken for releasing the cover when so desired.

Referring more in detail to the drawings, the container shown has a body portion 1. A closure 2 is provided for said body portion having a central depression 3 and a depending flange 4, said closure being adapted to have outside frictional engagement with the body portion when seated upon the same. The lower end of the depending flange 4 of the closure which extends down the body portion terminates in an out-turned bead 5. Integral lugs 6 are shown which extend down-

ward at a distance greater than the bead 5 and are adapted to be bent outwardly and inwardly and around said bead on the cover flange for retaining the closure in positive sealed relation with the body portion. A score line is provided at 6a which weakens the retaining lugs sufficiently so that they may be readily broken off for releasing said closure. A sealing compound 7 may be placed within the channel 8 which is formed between the central depression 3 and the outer flange 4 if so desired.

The invention is directed broadly to the manner in which the integral lugs are formed so that they may be positioned when the body portion and closure therefor is assembled, to retain the parts in sealed relation. As shown in Fig. 2 the body portion 1 is shown in blank form. Suitable retaining tabs 6 are notched out integral with one end thereof. A score line 6a is provided at substantially the point where the lugs terminate into the body portion. Before the body portion 1 in blank form is rolled the upper portion thereof containing the lugs is bent back upon itself as diagrammatically shown at 9 forming a depending portion 9a. It is then rolled and locked with the usual lock and lap seam and a bottom secured thereto in the well known manner. It may be readily seen in the drawings that the depth of the folded portion 9a is substantially equal to the depth of the cover flange 4 which allows the lugs 6 to protrude downward at a sufficient distance so that when the cover is in place upon the body portion, sufficient metal will be left in the length of the lugs for bending the same around the bead of the cover for retaining said cover in place.

It will be readily understood that other ways may be employed of forming lugs integral with the body portion of a container for retaining a closure in sealed relation thereon without departing from the spirit of the present invention, as set forth in the appended claims.

Having fully described my invention, what I claim as new and desire to secure by Letters Patent, is:—

1. A metal container including in combi- 106

nation a body portion, an outside slip cover having a depending flange provided with a bead at the lower edge, said body portion having holding lugs formed integral therewith adapted to bend outwardly and inwardly around said bead on the cover flange for securing said cover in sealing contact with the container body, said holding lugs being scored whereby they may be torn away and the cover released from the container body.

2. A metal container including in combination a body portion, an outside slip cover having a depending flange provided with a bead at its lower edge, said body portion being bent downwardly on the outer face thereof to an extent to equal the depth of the overlap of the cover flange, said body portion being provided with holding lugs formed integral therewith and adapted to be bent outwardly and inwardly around the bead on the cover flange for securing said cover in sealing contact with the container body, said holding lugs being scored whereby they may be torn away and the cover released from the container body.

In testimony whereof, I affix my signature.
WILLIAM F. PUNTE.
